Reuben Daniels
Peterson Patent

The Schedule referred to in these Letters Patent and making part of the same containing a description in the words of the said Reuben Daniels himself of his improvement "in Shearing Machines for shearing woolen cloths" for which Letters Patent were granted dated the 10th day of May 1834 which Letters Patent being, hereby, cancelled on account of a defective specification. To all to whom these presents shall come.

Be it known that I Reuben Daniels of Woodstock in the County of Windsor and State of Vermont, Machinist, have invented made and applied to use a new and useful improvement in Shearing, Machines for shearing, woolen, & other cloths an imperfect description & specification whereof has been heretofore given, a copy whereof is annexed to letter patent heretofore granted to me bearing date the thirteenth day of May in the year of our Lord one thousand eight hundred and thirty four and now discontinued as incomplete and which invention & improvement I do hereby accurately & perfectly, ^{describ} for the better understanding of my said invention & improvement drawings of a machine wherein my said improvement is made used & applied are herewith annexed numbered 1, 2, 3, as part of this specification. Drawing number one is an end view showing both ends of the machine. Drawing numbered two is a perspective view of the machine. Drawing numbered three is a front view of the machine. In Drawing No 1 Fig. 1 represents the bearings on which the rotating cylindrical cutter turns. Fig. 2 is the cast iron support to which the larger blade is fastened. Fig's 3, 3, 3, 3, 4 represent the spiral cut-^{ing}

back after it has passed the shears. This operation is performed by moving the gear P. by means of the lever S. placed in a groove running around the gear P. at the left hand end which gear P. runs loose on the driving shaft while the cloth is in the process of shearing, after the whole roll has passed the shears, the bell gives an alarm and the attendant moves the lever S. from right to left and the gear P. connects with the stationary gear on the driving shaft, and the motion of the cloth is reversed and the cloth again wound around the roll in readiness to be sheared a second time. During the process of shearing) the motion of the cloth in passing the shears turns the cloth roll and the gear O being meshed into the gear P. the latter gear P. turns like a loose pulley on the driving shaft. a. a. a. are ends of pins that go lengthwise of the frame. C. is the brush for raising the nap. d. is the brush for laying the nap. h. h. h. are screws to adjust the seats. M. & N. is a roll to tighten the cloth. L. is a flange on the roll M. to receive the screw O. In drawings numbered 243. the same letters & figures represent the same parts as in drawing numbered one. In drawing No 23 m. m. m. is a support to receive the screw O. which passing through the nut P. and being turned by the crank R. it moves the slide seat C. back and forward, on the other seat M. The several drawings No 143 and fig 1 in No 2. are upon a scale of three inches to a foot. The machines represented in the drawings are adapted for shearing cloth from end to end but the form, construction, proportions and materials thereof may be some what varied at the discretion of the machinist and the construction and form of machines adapted for shearing from left to right will of course be somewhat different but equally

formable to those now in use for that purpose except as necessarily varied or altered by my said improvement, but it is not intended particularly or minutely to describe all or any of the machines in which my said improvement is made or may be used or to which it may be applied, further than to shew in what and wherein my said improvement consists and the use and applications thereof. That part of my improvement herein after described which consists in the shearing rest for saving the listing or salvage is of course not to be used in the machines for shearing, from list to list. One part of my said improvement consists in the construction & use of the peculiarly constructed rotary cylindrical cutter herein described which is constructed as follows. The axis is a metallic bar of cast steel or other metal about one inch in diameter of sufficient hardness for bearings and of a length proportional to the length of the shear or rotary cutter proposed to be made. It is represented by fig. in fig. N° 2. in drawing N° 2. solid metallic wheels or heads of the diameter of the inside of the cylinder to be formed are to be prepared with holes in the centres through which the metallic bar aforesaid is to be passed, which holes are to be made so as closely to fit to the bar and which wheels are attached or fastened in their proper places to the said bar and said wheels or heads should be about one fourth of an inch in thickness and should have tenons or hubs at the centre of sufficient strength to support them, and at the periphery, should have flanges about one fourth of an inch thick and about three fourths of an inch broad. These wheels may be of brass or other metal but brass is deemed best. They are represented by fig. 3. in fig. 2. in drawing N° 2. Spokes with ends may be used instead of those solid wheels, but the solid wheels

wheels are preferred on account of their superior firmness and stiffness in proportion to their weight. The number of these metallic heads, wheels or spiders ought to be such as that they may be about ten or twelve inches apart from each other and of course must be more or less according to the length of the cylinder to be formed.

The number however may be somewhat varied at discretion having regard to the firmness of the cylinder to be formed. One of these heads, wheels or spiders is to be placed at each end of the cylinder and since the metallic sheets herein after mentioned are united to form the periphery of the cylinder, one of these heads, wheels or spiders should be put at each place where the sheets are united. On these heads, wheels or spiders a periphery made from sheets of tin copper or other suitable metal bent & made into the form of a cylinder with edges lapsing over each other firmly, soldered or fastened together, so that the inner surface may conform exactly to the periphery of said heads wheels, or to the rims of the spiders, is to be soldered or fastened firmly. Small strips of tin or other suitable metallic ^{plate} of about one half an inch in width having one of their edges bent up at right angles to the rest of about one eighth of an inch, are to be firmly soldered or fastened by the widest part around the periphery of the cylinder thus forming spirally like the blades of the rotary cutter now in use. The number of these strips is to be equal to the number of the cutting blades to be used, which may be from ten to twenty according to the diameter of the cylinder. The diameter of the cylinder may be from three to five inches or more. The back or iron side of the cutting blades are to be soldered to the outside of the lips or upright edges of the strips of tin or other metal soldered or fastened.

5/13/1834 8191X

turns to the cylinder as a foreguide, and the bottom or lower part of the front or steel side is to be soldered to the cylinder, a small body of solder being left in front to brace the blade of the cutter. Rotary cylindrical cutters constructed in this manner may be used for all purposes of shearing cloth for which the rotary cutter now in use is used. The cutting blades are similar to those now in the rotary cutter commonly used. Another part of my improvement and which is used only in shearing cloth from end to end consists in a double metallic rest or support, the upper part whereby is moveable in the place of the metallic support or rest now commonly used, enables me to hold the ledge blade to hold the cloth firmly in contact with the rotary cutter's ledge blade during the process of shearing. The under part of the metallic support or rest is made nearly like that now in use, excepting pieces of iron or other metal screwed on to keep the moveable rest in its proper place marked X. X. in Fig. 2. of Drawing No 2. Above this is a moveable rest of cast iron, brass or other suitable metal marked, i. on said last mentioned figure adapted and fitted to the rest or support beneath so that by turning a screw marked O. in the last named figure or by a lever or gearing the sliding rest may be made to move or slide upon the rest or support beneath it backwards or forwards so as to be accommodated to the width of the cloth in such manner as to permit the lifting or salvaging at one end of the rest to drop down from under the blades of the rotary cutter without being sheared, at the other end the lifting or salvaging is performed by being allowed to pass beyond the blades of the rotary cutter. The moveable rest may be made capable of being moved so as to save the lifting of cloths varying in width by means

5/13/1834 819/X

338

ing, the sliding rest from right to left & left to right as occasion may require. The form of the moveable rest is also shown by an end view in figures 34 & 35 (Drawing numbered two). In the construction of the rotary cutter instead of a metallic sheet or sheets, a hollow cylinder may be cast from brass or other suitable material & such strips of tin or other metal may be soldered thereto as aforesaid, and the blades may be soldered thereto as aforesaid but the metallic plate or plates is deemed preferable.

The sliding rest laps over the under rest at the top as represented in Figs 3 & 4 in (Drawing 34 & 35) so as to present a uniform surface for the cloth straight & even. Although I have described the machinery and apparatus of the whole of a shearing machine, yet it is to be understood that what I claim, and which I claim as new is as my invention & improvement is the construction of the rotary cutter with blades, wheels or spindles and a metallic sheet or sheets as aforesaid, or of cast metal rest as aforesaid, with the blades soldered thereto as aforesaid, and the use of rotary cutter so constructed & made in machines for the purpose of shearing woolen and other cloths, either from end to end or from list to list; and the construction & use of the sliding rest aforesaid, lapsing over as aforesaid, in the machine for shearing, cloth from end to end for the purpose of saving the listing or salving. I do witness that the above is a true specification of my said invention & improvement. I have here set my hand the twenty ninth day of July eighteen hundred and thirty-four.
